UNITED STATES PATENT OFFICE.

JOSEPH E. HOLBEIN, OF EVANS CITY, PENNSYLVANIA, ASSIGNOR TO
EDWARD DAMBACH, OF EVANS CITY, PENNSYLVANIA.

MANTEL.

SPECIFICATION forming part of Letters Patent No. 728,169, dated May 12, 1903.

Application filed March 19, 1903. Serial No. 148,562. (No model.)

To all whom it may concern:

Be it known that I, JOSEPH E. HOLBEIN, of Evans City, in the county of Butler and State of Pennsylvania, have invented certain new and useful Improvements in Mantels; and I hereby declare that the following is a full, clear, and exact description thereof, reference being had to the accompanying drawings, which form part of this specification.

10 This invention is an improvement in adjustable knockdown mantels; and its object is to so construct the mantels that short pilasters and full-length frieze may be retained, while permitting of ready adjustment to suit 15 fireplaces of different sizes, preserving the desired "colonial" style and admitting of any desired ornamentation of pilasters and frieze without interfering with the capability of adjustment of the mantel. The construction is 20 such that the mantel can be readily "knocked down" for shipment, packed in small space, and easily set up and adjusted with very little labor or cutting and when in position will 25 present the appearance of a specially designed or fitted mantel.

The invention resides particularly in the connection between the pilasters and frieze-board as hereinafter more particularly described and claimed, and the accompanying 30 drawings illustrate a mantel embodying my invention.

Figure 1 is a front view of the mantel with one pilaster connected to frieze-board and the other offset therefrom. Fig. 2 is a similar rear view of Fig. 1. Fig. 3 is an enlarged 35 detail vertical section on line 3-3, Fig. 2. Fig. 4 is a horizontal detail section on line 4-4, Fig. 2. Fig. 5 is a detail.

In said drawings, A represents the frieze-board of the mantel, supporting the shelf B, and it may be ornamented in any desired manner. To the lower edge of and rear side of the frieze-board A is attached a depending finishing-strip C, which is shorter than the 40 frieze-board and of a thickness corresponding to the thickness of the upper portion of the pilasters, which extend behind the frieze-board. The pilasters are preferably made compound, and, as shown, each consists of two

parallel rear strips or bars D E united by an 50 intermediate overlying parallel facing-board F, which may be ornamented in any desired manner. When the pilasters are in position, the upper end of strip D abuts against the lower edge of board C. The strip E extends 55 up behind board A, and its upper end abuts against the lower surface of the shelf B, projecting behind board A. The upper end of facing-board F is squared and abuts against the lower edge of board A. The strip D, it 60 will be noted, is shorter than board F, and it has a rabbet d in its upper end, forming a horizontal slot-groove between the upper ends of strip D and board F, which slot coincides with a reduced portion on tongue c 65 on the lower edge of board C, produced by channeling or recessing the lower rear side of said board near its ends, as shown at c'. These intermeshing tongues and grooves on the strips C and D form an interlocking 70 adjustable joint between the pilasters and frieze, as indicated in the drawings. By cutting off the ends of strip C the pilasters can be adjusted nearer to each other, and the height of the mantel can be reduced by cutting off the lower ends of the pilasters. When 75 adjusted to desired size, the pilasters are secured by nailing or screwing the upper ends of strips E to the board A, and the ends of strip D may be likewise fastened to board F, 80 as indicated in the drawings. The usual finishing molding-strip G g can be attached to the lower edge of the strip C and inner edges of the strip C and inner edges of boards D, and if the pilasters are to be brought closer 85 together it is simply necessary to remove the strip G, cut it the proper length, and replace it after the mantel is in position.

It will be observed that by having the fastenings between pilasters and frieze-board at 90 the extreme outside pieces it is possible to make the mantels in the greatest variety of designs without interfering with their capability for adjustment or knocking down. No cutting of the frieze-board or of the pilasters 95 is required for lateral adjustment of the mantel, and merely cutting the bases of pilasters provides for the vertical adjustment.

Having thus described my invention, what I therefore claim as new, and desire to secure by Letters Patent thereon, is—

1. A knockdown or adjustable mantel, having a frieze-board, a finishing-strip on the lower side of board, provided with recesses forming tongues on its lower edge near its opposite ends; pilasters having upstanding strips extending behind and adapted to be fastened 5 to the frieze-board, a facing portion adapted to abut the lower edge of the frieze-board, and an inner portion having a rabbeted upper end forming a slot for engagement with the tongue on the adjacent end of said finishing-strip, substantially as described.
2. In a knockdown or adjustable mantel, the combination of the frieze-board, a finishing-strip at the lower side thereof provided with recessed portions on its rear side and 10 lower edge forming tongues; laterally-adjustable pilasters comprising parallel strips and a facing-board, the outermost strip extending up in rear of and adapted to be fastened to the frieze-board, the facing-board extending 15 up to and abutting against the lower edge of the frieze-board, and the inner strip extending up to the finishing-strip, and having its

upper end rabbeted to form a groove for the reception of the tongues on the finishing-strip, substantially as described.

3. The herein-designed knockdown and adjustable mantel, comprising a frieze-board, a shelf attached to the upper edge thereof, a finishing-strip attached to the rear side thereof and extending below the same, said finishing-board having tongues *c* at its ends; with the laterally-adjustable pilasters composed of parallel strips and an outer facing-board connecting said strips, the outermost strip extending up behind the frieze-board and abutting against the shelf, the facing-board extending up to and abutting against the lower edge of the frieze-board, and the inner strip extending up to the finishing-strip and having its upper end rabbeted at *d* for the engagement with the adjacent tongue *c* on the finishing-strip, all substantially as described.

In testimony that I claim the foregoing as my own I affix my signature in presence of two witnesses.

JOSEPH E. HOLBEIN.

In presence of—

A. J. DAMBACH,
J. ADAM RIPPER.
